UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

FEEDING MECHANISM FOR RIVET-SETTING MACHINES.

Application filed May 8, 1924. Serial No. 711,767.

This invention relates generally to a device for delivering rivets one-at-a-time and in unbroken order to a rivet setting machine.

5 A general object of the invention is to provide an improved rivet feeding device of the hollow pick-up wheel type in which the rivets are fed into the pick-up member in such manner as to facilitate the pick-up and delivery operations of the pick-up wheel.

The invention includes a cup-shaped pick-up member provided along its marginal portion with a series of rivet receiving slots so formed and arranged as to receive individual rivets which are properly disposed for the purpose in a mass of rivets resting on the slotted portion of the wheel as it rotates. The rivets are fed into the open end of the cup-shaped pick-up member 20 from a suitable supply hopper and a rivet delivery chute is arranged to receive the arranged rivets from the pick-up slots as the wheel rotates.

A feature of the invention resides in the 25 structure of the rivet supply member through which rivets are delivered into the pick-up member for arrangement and delivery thereby to the rivet delivery chute. This construction consists in a rivet feeding passageway arranged to deliver rivets in a direction substantially tangential to the circular inner surface of the pick-up wheel and in the same general direction of movement in which the wheel travels.

35 Other features of the invention will be hereinafter referred to.

In the drawings in which a preferred embodiment of the invention has been selected for illustration,

40 Figure 1 is a view in front elevation and partly in section of a rivet feeding device embodying the invention.

Figure 2 is a view in vertical section taken on the lines 2-2 of Figure 1.

45 Figure 3 is a view similar to Figure 1 with a portion removed and another portion shown in section.

Figure 4 is a view in vertical section taken on the lines 4-4 of Figure 3.

50 Referring to the drawings for a more detailed description of the invention, a rivet feeding device is shown which consists of a rivet supply hopper 10 carried by a frame piece 11 in which there is journaled a shaft 12 adapted to support and ro-

tate a cup-shaped rivet pick-up member 13 which is held in position against a shoulder 14 on the shaft through a wing nut 15 and an interposed spring washer 16.

The frame member 11 is so formed as to provide a flange or shoulder 17 within which the outer periphery of the pick-up member 13 rotates, the marginal portion of the pick-up member being provided with slots 18 in which individual rivet members 19 are received as the pick-up wheel rotates. The rivets which are so disposed in the pile or mass as to be received in the slots 18 are thereupon carried in a clockwise direction as the device is viewed in Figure 1 of the 70 drawing to the peripherally arranged passageway 20 which leads directly into the receiving end of a rivet delivery chute 21, the chute 21 leading downwardly from the feeding device to the setting mechanism of the 75 machine with which the device is associated.

A feature of the invention resides in the manner in which rivets are delivered or supplied to the rotating pick-up member 13. It will be seen that the rivet supply hopper 80 10 feeds directly into a passageway 22 which extends into the interior of member 13 and which terminates in a delivery spout 23 having a discharge orifice or port 24. It will be seen that the mouth of the orifice 24 is 85 so positioned within and with respect to the adjacent surface 25 of the pick-up wheel as to deliver rivets in a direction substantially at a tangent to the direction of rotation of the pick-up wheel and also in the general 90 direction of movement of the adjacent parts of the wheel. By reason of this relation of the delivery spout 23 to the inner surface of the pick-up wheel 25 rivets are supplied to the pick-up wheel at a convenient location for immediate delivery of the rivets by way of the slots or passages 18 directly to the passageway or groove 20 which leads to the rivet delivery chute 21. The operation of transferring rivets from the supply 95 hopper 10 to the delivery chute 21 is thereby greatly facilitated and the uniform and uninterrupted supply of rivets to the delivery chute 21 is insured.

In operation the cup-shaped pick-up member 13 is intermittently rotated through a step by step rotation of the ratchet wheel 26 carried by the inner end of the shaft 12, the rotation of the ratchet 26 being achieved in any desirable or suitable manner. The 110

intermittent motion of the pick-up member which is thus provided has been found to be particularly suitable for the purpose in that the agitation and disturbance of the mass of rivets which is thereby obtained assists in the deposit of properly disposed rivets in the receiving slots 18.

Preferably a shield or guard member 27 is provided with the upper part of the pick-up member 13 and for convenience the guard member is attached directly to the forward face of the hopper 10. The guard member 27 prevents the accidental dropping of rivets into the exposed slots of the pick-up member from the outside as well as overcoming the possibility of injury to the hands of an operator.

In operation the rivets are delivered into the pick-up member and naturally assume a pile or mass formation as indicated in Figure 3 of the drawing. The rotation of the pick-up member produces a tumbling action of the rivets wherein such rivets as are properly disposed for the purpose find their way into the receiving slots 18 and are thereby carried to delivery points adjacent the receiving end of the delivery chute 21 whence they find their way to the setting device below.

30 What is claimed is:

1. In a rivet feeding device, a hollow rotatable rivet feeding member and means including a delivery spout within said member for delivering rivets into the member in a direction substantially coincident with the direction of travel thereof.

2. In a rivet feeding device a rotatable cup-shaped rivet feeding member having pick-up slots formed in the margin thereof, and means extending into said cup-shaped member for delivering rivets into the feeding member in a direction substantially coincident with the direction of travel.

3. In a rivet feeding device, a rotatable cup-shaped rivet feeding member having pick-up slots formed in the margin thereof, and means for delivering rivets into the feeding member including a passageway within the cup-shaped member having a discharge orifice for delivering rivets substantially tangentially of and directly into the path of rotation of the slotted portion of the pick-up member.

4. In a rivet feeding device, a hollow rotatable rivet feeding member formed to pick up and deliver rivets disposed in a certain position, and means extending into said hollow feeding member for delivering rivets into the feeding mechanism in a direction substantially tangential to and in the direction of travel of the pick-up member.

5. In a rivet feeding device, a rotatable cup-shaped rivet feeding member having pick-up slots formed in the margin thereof, and means extending into the open end of the cup for delivering rivets thereto in a direction substantially at a tangent to and in the direction of travel of the rotatable rivet feeding member.

6. In a rivet feeding device, a rotatable cup-shaped rivet feeding member having pick-up slots formed in the margin thereof, a supporting frame member for the rivet feeding member, said frame member being provided with a rivet delivery chute extending into said cup-shaped member for receiving rivets from said feeding member, and said frame member having a rivet supply passage arranged to deliver rivets through the open side of said cup-shaped member and against the slotted portion in the vicinity of the receiving end of the delivery chute.

In testimony whereof I affix my signature.

EDWIN B. STIMPSON.
